UNITED STATES PATENT OFFICE.

CHRISTIAN STICHER, OF LEIPZIG, GERMANY, ASSIGNOR TO RUDOLF GAERTNER, OF NEW YORK, N. Y.

DESIGN FOR AN ARTICLE OF MANUFACTURE.

45,659.

Specification for Design.

Patented Apr. 21, 1914.

Application filed February 28, 1914. Serial No. 821,811. Term of patent 3½ years.

To all whom it may concern:

Be it known that I, CHRISTIAN STICHER, a subject of the German Emperor, and resident of Leipzig, Germany, have invented a new, original, and ornamental Design for an Article of Manufacture, of which the following is a specification, reference being had to the accompanying drawing, forming part thereof.

The figure is a face view of an article of manufacture showing my new design.

I claim:

The ornamental design for an article of manufacture, as shown.

CHRISTIAN STICHER.

Witnesses:

RUDOLPH FRICKE,
DORIS KRAHL.
